(57) **CLAIM**

The ornamental design for a flying automobile, as shown and described.

DESCRIPTION

FIG. 1 is a perspective view of a flying automobile showing my new design with the wings, canard and wheel structures disposed in folded and retracted condition for road travel operation of the flying automobile of this design.

FIG. 2 is a right side elevational view of the automobile of FIG. 1.

FIG. 3 is a left side elevational view thereof.

FIG. 4 is a top plan view as viewed from the top in FIG. 2.

FIG. 5 is a front end elevational view taken from the right in FIG. 2.

FIG. 6 is a rear end elevational view taken from the left in FIG. 2.

FIG. 7 is a bottom plan view thereof.

FIG. 8 is a perspective view of the flying automobile of FIGS. 1-8 but showing the automobile with the wings, canard and wheel structures deployed in unfolded and extended condition for flying operation of the flying automobile of this design.

FIG. 9 is a right side elevational view of the vehicle of FIG. 8.

FIG. 10 is a left side elevational view thereof.

FIG. 11 is a top plan view as viewed from the top in FIG. 9.

FIG. 12 is a front end elevational view taken from the right in FIG. 9.

FIG. 13 is a rear end elevational view taken from the left in FIG. 9; and,

FIG. 14 is a bottom plan view thereof.
